ANNEALING FURNACE

Claude Nagle, Elmira, N. Y.

Application June 8, 1933, Serial No. 674,937

10 Claims. (Cl. 49—47)

My invention relates to annealing furnaces or leers and more particularly to a leer of the continuous type used in annealing glassware and the like.

5 Heretofore, it has been proposed to construct leers of the continuous type wherein the articles to be annealed are passed through the annealing chamber by means of an endless conveyor. In the prior art devices the annealing chamber is 10 heated by one or more burners connected with suitable flues or passages, whereby the top and bottom of the chamber is exposed to the heated gases. With these arrangements considerable difficulty has been experienced in controlling the 15 temperature within the annealing chamber for the reason that in only heating the bottom and top, areas which are cooler than the top or bottom are formed along the sides of the chamber. This results in exposing the articles to be annealed, which are near the edges of the conveyor, to the cooler areas with resultant lines of stress or strain being set up with the material which may cause cracking or breaking of the article.

Another inherent difficulty experienced with 25 leers of conventional design, is method of introducing the materials into the annealing chamber. According to present practice, the articles are placed upon the endless conveyor near the front end of the chamber and are moved forwardly at 30 a predetermined speed. Since the articles which are first placed on the conveyor are the first to enter the chamber, they are obviously much hotter than those which are subsequently placed on the conveyor. As soon as a given group of 35 the ware to be annealed is within the chamber the articles in that group are of necessity at various degrees of temperatures and during the annealing step are subjected to a temperature which frequently causes cracking or formation of lines of 40 strain in the ware.

It is the purpose of the present invention to overcome the above noted difficulties as well as others by means of an improved furnace structure 45 wherein the fire boxes are arranged and connected through suitable passages and flues whereby the interior of the annealing chamber is uniformly heated. The invention also includes an arrangement adapted to initially bring the ware to be annealed to a uniform temperature 50 before it is introduced into the annealing chamber, and means are provided to obtain proper temperature control after the ware leaves the chamber.

55 An object of my invention is to provide a leer

having an improved fire box arrangement whereby the heating of the chambers is maintained at a substantially uniform temperature.

Another object of my invention is to provide a 5 leer having a pre-heating zone adapted to bring the ware to be annealed to a uniform temperature before it is introduced into the annealing chamber.

Yet another object of my invention is to provide a leer having an improved tunnel arrangement 10 adapted to permit expansion and contraction of its parts during the normal operation without any bulging or displacement of the lining.

Still another object of the invention is to provide a 15 leer having an improved cooling arrangement associated with the cooling zone whereby the ware is efficiently cooled, after it leaves the heating chamber.

A further object of the invention is to provide an improved driving arrangement for the end- 20 less conveyor used to convey the ware through the leer.

With these and other objects in view, which may be incident to my improvements, the invention consists in the parts and combinations to be 25 hereinafter set forth and claimed, with the understanding that the several necessary elements, comprising my invention, may be varied in construction, proportions and arrangement, without departing from the spirit and scope of the 30 appended claims.

In order to make my invention more clearly understood, I have shown in the accompanying drawings means for carrying the same into practical effect, without limiting the improvements in 35 their useful applications to the particular constructions, which for the purpose of explanation, have been made the subject of illustration.

In the drawings: 40
Figure 1 is a side elevational view of a leer.

Fig. 2 is a plan view of the arrangement shown in Figure 1.

Fig. 3 is a vertical sectional view of the equalizing zone, the heating zone and the holding zone 45 of the leer.

Fig. 4 is a sectional view along line C—C of Fig. 5 showing the arrangement of the flues in the vicinity of the equalizing and heating zones.

Fig. 5 is a sectional view along line A—A of Fig. 4 showing the arrangement of the fire boxes and tunnel.

Fig. 6 is a sectional view along line B—B of Fig. 5.

Fig. 7 is a sectional view along line D—D of Fig. 5; and

Fig. 8 is an elevational view of the endless conveyor drive mechanism.

5 Referring to the drawings and more particularly to Figures 1 and 2, there is shown a leir or furnace having a preheating or equalizing zone A, a heating zone B, a holding zone C and a cooling zone D. Near the end of the cooling zone, 10 there is provided a suitable packing table T adapted to receive the ware after it has been annealed. The furnace is mounted upon suitable supports 1 and is provided with reinforcing bands or straps 2 throughout its length.

15 The articles to be annealed are moved through the various zones of the leir by means of an endless belt 3 mounted upon rollers 4 and adapted to be driven by means of a motor 5 and its associated equipment 6. Mounted upon the top 20 of the furnace is a motor 7 adapted to drive a suction fan or blower 8 having an inlet 9 and an outlet 10. The inlet of the fan is connected to a pair of conduits 11 extending along either side of the furnace and connected with ports 12 opening into the holding zone. The conduits are provided with suitable dampers 13 whereby the flow of heated gases from the holding zone to the outlet may be properly controlled.

25 Referring to Figure 3, it will be seen that the bottom of the leir is made up of a plurality of plates 14 resting upon and supported by transverse beams 15. The plates 14 are not fastened to the beams, but are so mounted that they are free to move due to contraction and expansion, 30 movement of the plates in the direction of the length of the furnace being limited by means of stops or projections 16 formed on the bottom of the plates. The top of the furnace is supported by means of a plurality of I-beams 17 and the 35 entrance to the equalizing zone is provided with a vertical adjustable gate or sliding door 18, adapted to be moved by means of a suitable operating mechanism.

40 Referring to Figures 5 and 6, there is shown 45 sectional views through the heating zone. It will be noted that the leir is provided with two fire boxes, one on either side of a central partition member 19, which are equipped with burners 19', combustion chambers 20 and passages 21. Since 50 each half of the furnace is identical, the description will be limited to one side only. The heated gases pass from the combustion chamber 20 through the passage 21 and along the side of the furnace into the conduit 22 at the top of the heating chamber as shown by the arrows. As will be seen from Figure 6, the heated gases are 55 divided after they pass from the combustion chamber and discharge into the conduit or flue 22 by means of separate paths. With this arrangement, equal distribution of heat is obtained 60 along the sides of the furnace.

65 From the description thus far, it will be seen that the leir is heated along a portion of the bottom, at sides and top by means of two fire boxes having separate burners therein. The flow 70 of heated gases from the combustion chamber is along the bottom, up the sides, and across the top into the central flue or conduit extending longitudinally of the furnace. The interior of the furnace proper is in the form of a tunnel made up of the bottom and side linings together with the longitudinal flues. In this connection it will 75 be noted that the tunnel is arranged so that it is freely floating, in order that expansion and con-

traction of the plates will not cause bulging on the interior of the furnace. The specific supporting arrangement for the tunnel will be described more fully hereinafter.

5 The bottom of the tunnel, as already indicated, is formed with plates 14 and on either side thereof, are pieces 23 adapted to withstand the effects of the highly heated gases which pass in proximity to the edge and bottom of the tunnel. The plates 14 are bolted or fastened by means of bolts 10 24 at one end thereof, to the material 23. Exterior of the tunnel, the bottom, top and sides of the furnace, are provided with suitable refractory material in the form of bricks 25 and the outer 15 surface of the furnace is formed of packing material 26.

Extending crosswise of the fire box and near the bottom thereof, is a conduit 27 having an outlet 28 into the combustion chamber whereby air may be supplied to the burners in order to support combustion. Above the combustion chamber and extending transversely of the furnace, there is provided a plurality of beams 29 adapted to support pillars 30 upon which the members 31 forming the lining for the side of the tunnel are 25 mounted. As shown in Figure 6, the I-beams 17 rest directly on top of members 31 and rollers 4 which support the endless belt, are attached to the bottom of the furnace by means of brackets 32. 30

Referring to Figure 4, it will be seen that the conduit 22 is made up of a plurality of sections 33 resting upon and supported by the flanges 34 of the I-beams 17. The sections 33 are substantially T-shaped hollow members, the arms of which seat in openings formed in the webs of the I-beams 17. These sections are also provided with projections 35 which rest on the flanges 34 and between each of the sections forming the longitudinal flue 22 of the heating chamber, connecting members 36 are provided. These members are likewise hollow and are formed with reduced portions 37 adapted to fit into the openings formed in the I-beams 17 and provide a continuous passage for the heated gases. The side 40 plates 38 are formed with projections or arms 39 providing a groove or channel adapted to receive refractory material 38 in the form of brick sections. 45

It will now be seen that the I-beams 17 rest 50 upon the top edges of the plates 31 and that the hollow sections 33 and 38 are supported by the flanges of the beams. Since the webs of the beams are provided with openings adapted to receive the ends of sections 33 and 38, a continuous 55 passage is provided for the hot gases along the top of the leir. The gases pass upwardly from the fire boxes along the sides of the heating chamber through ports 21' into sections 33, then through the openings in the webs of the beams 60 into sections 38 and after passing through these sections, are joined with the gases coming from the other ports 21'.

Near the front of the leir, there is provided a 65 port 40 connected by means of suitable passages with the combustion chambers. The hot gases pass through this port into the longitudinal flue 22 at the top of the equalizing zone of the leir. The portion of the leir between the equalizing 70 zone and heating zone is made up of a plurality of sections similar to the connecting means 36 between the sections 33 forming that part of the flue within the heating zone. The first section 41 of the flue is provided with a side piece 42 having 75

projections 43 formed thereon, adapted to seat on the inside flange of the first transverse I-beam, and the interior side walls of the equalizing zone are formed with refractory material 44, held in position between the vertical beams 45.

The flue 22 extends from the front end of the leir through the equalizing zone and terminates at the end of the heating chamber. The last section 46 at the end of the heating chamber is similar to the section 41 at the entrance to the equalizing zone and after the gases have passed through the equalizing and heating zones, they enter passage 47 and continue down along the sides of the leir through the holding and cooling zones.

In order to properly control the temperature within the cooling zone, suitable dampers 48-49 are provided, as more clearly shown in Figure 2. The dampers are formed with blades or flaps 49 pivoted about an axis 50 and adapted to be opened or closed by suitable mechanism not shown. In this connection, it will be noted that the dampers are placed centrally of the leir and provide means for withdrawing the heated gases by natural draft from the center of the zone, thereby effecting a gradual withdrawing of the gases from the point at which the temperature is the highest.

Referring to Figure 7, the beams 29 are provided with projections 51 and the plates 14 are formed with cut-out portions 52 adapted to fit around the projections 51. The purpose of this arrangement is to limit the longitudinal movement of the plates when they expand due to the high temperature to which they are subjected. In order to maintain the plates 14 in a horizontal position, the clips 53 are provided, which overlap the edges of adjacent plates.

Referring to Figure 8, the driving arrangement for the endless belt comprises a motor 54 having a base 55 mounted upon support members 56. The motor is provided with a pulley 57 adapted to drive a belt 58 connected with a pulley 59 mounted upon a drum 60. After the endless belt or chain 3 leaves the packing table, it passes around an idler pulley 61, then around drum 60, over adjustable pulley 62 and back to the front end of the leir.

In order to increase the effective area of contact between the endless belt and the drum 60, and to also provide for the proper tensioning of the belt, pulley 62 may be adjusted longitudinally of its support 63. Between the pulley frame 64 and a fixed support 65, there is mounted a spring 66 adapted to be compressed when excess compression is placed upon the pulley, the tension of the spring being adjusted by means of a set screw 67. It sometimes happens that dirt or other foreign matter adheres to the belt and if the tensioning pulley were not free to move, the excess compression between roller 62 and the surface of the belt might injure the belt or cause breakage of the pulley.

While I have shown and described the preferred embodiment of my invention, I wish it to be understood that I do not confine myself to the precise details of construction herein set forth, by way of illustrations, as it is apparent that many changes and variations may be made therein, by those skilled in the art, without departing from the spirit of the invention, or exceeding the scope of the appended claims.

What is claimed is:

1. In an annealing furnace of the continuous type including a fire box, a heating chamber

formed of a plurality of bottom, side and top sections, the top sections being hollow and interconnected by means of hollow coupling members to form a conduit extending longitudinally of the chamber, each of said top sections communicating by means of separate gas passages with the fire box.

2. In an annealing furnace of the continuous type, a heating chamber formed of a plurality of individual bottom, side and top sections, each 10 of said top sections being hollow and freely movable with respect to and unattached to any other section, whereby any one of the top sections may expand or contract independently of the other sections, and means for supplying a gaseous heat- 15 ing medium to the interior of said top sections.

3. A leir of the continuous type having a central tunnel formed of a plurality of individual bottom, side and top sections, the bottom sections being unconnected and free to move independ- 20 ently of each other in the plane of the bottom of the tunnel, the top sections being hollow and interconnected to form a passage for a gaseous heating medium and a fire box communicating with said passage. 25

4. In a leir of the continuous type including a source of heat, an inner tunnel formed of a plurality of bottom, side and top sections, said top sections being hollow and interconnected by means of hollow coupling members to form a 30 conduit extending longitudinally of the leir, said conduit being connected to the source of heat by means of flues including passages in the rear of certain of the side sections, whereby the heated gases pass around the bottom, upwardly of the 35 sides and to the top of the leir to heat the interior of the chamber.

5. In a leir of the continuous type including a source of heat, an inner tunnel formed of a plurality of bottom, side and top sections, means to 40 support the top sections comprising a plurality of transverse members mounted in spaced relation lengthwise of the leir, said members having openings formed therein adapted to receive the ends of said sections, the top sections being hollow 45 and interconnected to form a conduit extending longitudinally of the leir, said conduit being connected to the source of heat by means of flues including passages in the rear of certain of the side sections. 50

6. In a leir of the continuous type including a source of heat, an inner tunnel formed of a plurality of bottom, side and top sections, means to support the top sections comprising a plurality of I-beams mounted in spaced relation length- 55 wise of the leir, said I-beams having openings formed in the web portions thereof adapted to receive the ends of said sections, the top sections being hollow and interconnected to form a conduit extending longitudinally of the leir, said 60 conduit being connected to the source of heat by means of flues including passages in the rear of certain of the side sections.

7. In a leir of the continuous type including a source of heat, an inner tunnel formed of a plurality of bottom, side and top sections, means to support the top sections comprising a plurality of transverse members mounted in spaced relation lengthwise of the leir, said members having openings formed therein adapted to receive the 65 ends of said top sections, the top sections being hollow and interconnected by means of hollow coupling members to form a conduit extending longitudinally of the leir. 70

8. In an annealing furnace of the continuous 75

type, an inner tunnel formed of a plurality of bottom, side and top sections, means to support said top sections comprising a plurality of I-beams having openings formed in the web portions thereof, said top sections being hollow and substantially T-shaped, the ends of the T portion being positioned in the openings formed in the webs of the I-beams, the top sections being interconnected by means of hollow coupling members positioned between successive supports to form a freely floating conduit extending longitudinally of the leer.

9. In a glassware annealing leer including an outer tunnel composed of insulating material and a structural framework, an inner tunnel including a wall-forming portion of hollow construc-

tion, unattached either to other portions of said inner tunnel or to said framework and free to expand and move when heated, and means for supplying a gaseous heating medium to the interior of said hollow wall-forming portion. 5

10. In a glassware annealing leer including an outer tunnel composed of insulating material and a structural framework, an inner tunnel having its top formed of hollow portions unattached either to other portions of said inner tunnel or to said framework and free to expand and move when heated, and means for supplying a gaseous heating medium to the interior of said hollow portions. 10

CLAUDE NAGLE. 15
